UNITED STATES PATENT OFFICE.

WILLIAM L. BEALL, OF ALBION, MICHIGAN, ASSIGNOR TO GALE MANUFACTURING COMPANY, OF ALBION, MICHIGAN.

RIDING OR WALKING CULTIVATOR.

SPECIFICATION forming part of Letters Patent No. 734,657, dated July 28, 1903.

Application filed November 18, 1902. Serial No. 131,864. (No model.)

To all whom it may concern:

Be it known that I, WILLIAM L. BEALL, a citizen of the United States, residing at Albion, in the county of Calhoun and State of Michigan, have invented certain new and useful Improvements in Riding or Walking Cultivators; and I do hereby declare the following to be a full, clear, and exact description of the invention, such as will enable others skilled in the art to which it appertains to make and use the same.

My present invention relates to the class of cultivators, and more particularly to that class which may be used as both riding-cultivators and walking-cultivators; and my said invention consists in certain improved constructions and combinations of parts whereby new and desirable results are obtained.

In the accompanying drawings I have illustrated the best form in which I have contemplated embodying my invention, and said invention is disclosed in the following description and claims.

Figure 1 is a perspective view of a riding-cultivator embodying my improvements, the wheel on the view side being removed. Fig. 2 is a longitudinal vertical section. Fig. 3 is a transverse vertical section on line $x-x$; Fig. 2. Fig. 4 is a detail of the axle-adjusting devices and the mechanism for lifting the cultivator-beams. Fig. 5 is a detail showing the guiding foot-levers and means for mounting the same. Figs. 6, 7, and 8 are details of parts of the cultivator-frame.

In the figures of the drawings, A A are the side bars of the main frame, which extend forward and are pivoted to the tongue D at d. The rear ends of these side bars are pivotally connected to the arched axle B. At the front of the machine an arched draft-bar C is rigidly secured to the side bars A A, and this draft-bar is further held in position by the braces c c. The lower ends of this draft-bar are provided with outward extensions c' c'. Upon these lateral extensions are placed sleeved castings E, each of which is provided with an arm e, having a number of holes by which attachment can be made for draft purposes, and the arm e', to which the hook e' is secured. A spring E' is secured to this hook, which at its upper end is connected to the

main frame by means permitting of adjustment. To the sleeved casting E is bolted the hinge-piece e³ and the standard e⁴. The plow or cultivator beams F' are pivoted to the hinge-piece e³, and a lifting-bar F is secured to the standard e⁴, and the said lifting-bar is also connected to the pivot of the hinge. To the rear end of the lifting-bar is secured the casting G, provided with a horizontal outwardly-extending flange g, having a hole therethrough, through which passes the lifting and depressing rod g', having springs g³ g⁴ upon the same above and below the said flange g. The upper end of the rod g' is forked and pivoted to the hand-lever G', the forked portion of the rod g' being provided with a number of holes to permit of adjustment. The lever G' is pivoted to the frame of the machine and is provided with a pawl to engage the notched segment G². The spring on rod g' above the flange g bears on the top of the flange and on the under side of a collar g², provided with a set-screw. The tension of the springs upon the rod g' can therefore be regulated by adjusting said collar up or down, as desired.

It will be seen that the lifting-bar F while controlling the vertical position of the plow or cultivator beam has its vertical position controlled by the lifting-rod g' and lever G' and that the plow or cultivator beam is maintained in its position by spring-pressure, permitting it to move upward or downward, as the ground passed over may demand, but that it will be returned to the normal position when this exigency has been passed. It will also be seen that the plow or cultivator beam will swing laterally in a straight line in whatever position it may be in. The casting G is also provided with a socket g³, to which is secured a bar H, which extends outwardly and rearwardly. To the rearwardly-extending portion of this bar is secured the offset bar h, the main portion of which extends parallel to the bar H and with said bar forms a guiding-slot through which passes a downwardly-extending portion of the arched axle B.

To the horizontal portion of the axle, at one side of the machine, is secured the casting I. (See Fig. 8.) This casting is divided on one side and is provided with the ears i i,

- through which a bolt i passes and secures the casting to the axle. The casting is further provided with an ear i^2 . A bar I' is secured to the main frame of the machine and extends rearwardly of the axle. To the rearward portion of the bar I' is secured the notched segment I^2 , which has a portion projecting below the bar I' , and to this portion of the segment is pivoted the hand-lever I^3 . The lower end of this lever is connected by link i^3 to the ear i^2 on the casting I . The lever I^3 is provided with a pawl to engage the notched segment and hold it in position. By this construction the lower ends of the axle can swing backward or forward to bring the weight of the frame of the machine forward or backward in respect to the axle to accommodate the varying conditions of the cultivator when in use, more especially to regulate the amount of weight upon the necks of the draft-animals in case of a change from a riding to a walking cultivator, and vice versa.
- To the inside of each plow or cultivator beam is secured the eye j , and to the inside of each of the side bars A of the frame is secured the bracket a . Bars J are pivoted to the said brackets a and pass downward through the eyes j , loosely engaging the same, so that the said cultivator or plow beams are free to rise or fall to suit the inequalities of the surface over which the cultivator may pass. These bars J are adjustably connected by the following construction, which is most clearly shown in Fig. 6.
- To the middle or slightly below the middle of the bars J are pivoted the bars K K' . These bars extend upwardly toward each other and crossing are pivoted to each other at k . Above the point of pivoting the bar K is bent backward upon itself to form the notched segment k' , and to the upper end of the bar K' is secured the rearwardly-extending bracket, to which is pivoted the hand-lever k^3 , which engages the notches of the notched segment k' . A spring k^4 serves to keep the lever k^3 in engagement with the notched segment k' . When the lever k^3 engages one of the notches in the segment, the bars J J and the plow or cultivator beams are held a certain distance apart and move in unison laterally.
- The side bars A A are each provided with a bracket a' , extending above said bars, and to these brackets are pivoted the seat-bars L , which extend rearwardly and support the seat L' .
- When used as a riding-cultivator, the plow or cultivator beams may be moved laterally by the feet of the operator by the following means: To the rearwardly-extending bars H are secured the brackets M , having the vertically-extending bearing m . In each of these bearings is movably fitted the journal of a controlling-lever N . This lever has an opening through the same, and through such opening passes a stirrup-rod n , provided with a stirrup N' . This rod n is secured in place by a set-screw n' , and the stirrup is secured, also adjustably, upon the rod n by a collar n^2 and set-screw n^3 . The lever N extends forwardly from its bearing and the forward end is connected by link n^4 with an ear f upon the plow or cultivator beam. By this means the plow or cultivator beams are moved to left or right by the feet of the operator without in any manner affecting the freedom of the plows or cultivator to rise or fall to conform to the surface of the ground. Upon the elevated portion of the arched draft-bar C is secured the bracket D' , having its forwardly-extending portion bifurcated to receive the rear end of the tongue D . The bifurcated portions of this bracket are slotted to receive a bolt by which the end of the tongue is adjustably secured to the frame of the machine.
- It will be seen that by mounting the stirrup-levers to move with the lifting-bars the foot control of the operator over the lateral movement of the beams is unaffected by the vertical position of the beams themselves and that the connection between the beams does not restrain in any way the free and independent movement of the said beams.
- What I claim, and desire to secure by Letters Patent, is—
- In a cultivator adapted to be used as a riding-cultivator, the combination with the lifting-bars for raising the hinged cultivator-beams and permitting the said beams to move laterally in a straight line, of foot-operated means movable with the said lifting-bars and connections with the cultivator-beams for moving said beams laterally at whatever elevation they may be, substantially as described.
  - In a cultivator adapted to be used as a riding-cultivator, the combination with the lifting-bars for raising the hinged cultivator-beams and permitting said beams to move laterally in a straight line, of stirrups mounted to rise and fall with said lifting-bars, and means connecting the said stirrups and cultivator-beams for moving said beams, substantially as described.
  - In a cultivator adapted to be used as a riding-cultivator, the combination with the lifting-bars of the hinged cultivator-beams, levers mounted to rise and fall with the lifting-bars, stirrups for controlling said levers and links connecting said levers and the said cultivator-beams, substantially as described.
  - In a cultivator having an arched axle and adapted to be used as a riding-cultivator, the combination with the lifting-bars, and hinged cultivator-beams, of stirrups mounted to rise and fall with the said lifting-beams, means connecting said stirrups and cultivator to permit the said stirrups to move the said beams laterally and for causing said beams to move in unison, said means not interfering with the passage of the growing plants beneath the arch of the axle, substantially as described.
  - In a cultivator adapted to be used as a

riding or walking cultivator, the combination with an arched axle having a pivotal connection with the main frame, guiding means for the downwardly-extending portions of the 5 axle, of a lever and means connecting said lever and axle to turn said axle to different positions to adjust the weight of the machine forwardly or rearwardly of said axle, substantially as described.

6. In a cultivator adapted to be used as a riding or walking cultivator, having an arched axle pivotally connected with the main frame, the combination with said axle, of a hand-lever, a link connecting it with the said axle 15 to turn the axle to adjust the weight of the machine more or less forward or back of the said axle, said frame being provided with guides for said axle, substantially as described.

7. In a cultivator adapted for use as a riding-cultivator, the combination with the cultivator-beams, of lifting-bars for lifting the cultivator-beams but permitting the said beams to move laterally in a straight line,

stirrups moving with said lifting-bars, and 25 operatively connected with the cultivator-beams, vertical bars loosely engaging said cultivator-beams, permitting said beams to move freely in a vertical direction and an adjustable connection between said vertical 30 bars, holding them a fixed distance apart, substantially as described.

8. In a cultivator adapted to be used as a riding-cultivator, the combination with the cultivator-beams, of the lifting-bars, the vertical bars having a loose engagement with the cultivator-beams, said vertical bars being connected by means including a pawl and notched segment for adjusting their distance apart, and stirrups connected with the said cultivator-beams moving with the said lifting-bars, 35 40 substantially as described.

In testimony whereof I affix my signature in the presence of two witnesses.

WILLIAM L. BEALL.
